UNITED STATES PATENT OFFICE

2,206,029

DEFORMABLE FOOT SUPPORT FOR SHOES

Claude H. Daniels, Wellesley Hills, Mass.

Application December 24, 1935, Serial No. 56,610

7 Claims. (Cl. 36—71)

This invention relates to improvements in foot supports and shoes having built-in foot supports in which the foot supports are formed of or include material that is transformable upon heating, whereby the foot supports may be caused to receive and retain a foot impression.

I have disclosed in my application Serial No. 44,038 filed October 8, 1935, and in Patents Nos. 2,092,909 and 2,092,910, certain improvements in deformable foot supports which may be caused to receive and retain foot impressions, and to serve as permanent supports for the individual feet to which they are molded. For the most part, such prior disclosures are directed to foot supports having fillers moldable at normal temperatures.

A patent to Lettermann 1,856,394, May 3, 1932 for Device for taking foot impressions, describes a device consisting of a flat chamber formed by an elastic envelope which is filled with a molten mass of paraffin and wax. The foot is placed upon the chamber filled with the molten mass and the foot is kept in position until the mass has solidified.

It is an object of my invention to disclose improvements in foot supports which are moldable at elevated temperatures and in particular the foot support is made moldable or otherwise transformed by heating from within the mass of filling material or by external heating of the foot support from heating elements forming parts of the shoes.

Specifically, it is an object of my invention to incorporate electrical heating elements in the foot supports or in the shoes.

A further object is the use of a flexible but inelastic envelope for the thermoplastic filling material instead of an elastic envelope.

Another object is the use of metallic members for the foot supports comprising alloys which become plastic and moldable upon heating, such metallic foot supports either do not require a retaining envelope or may include a coating or shell of metal which is thin enough to be flexible, but has a higher melting point than the body metal.

Further objects and advantages of my improvements will be more readily apparent from the following description.

In the drawing:

Fig. 1 is an elevation view of a shoe partially shown in section;

Fig. 2 is a cross section taken on the plane indicated 2—2 in Fig. 1; and,

Fig. 3 is a cross section showing a modified construction.

The shoe disclosed in Figs. 1 and 2 has the customary upper 10 fastened to the outsole 12 and insole 14 and having a heel 16 fixed to the outsole. A foot support comprising an envelope 18 and a filler 20 is placed in the shoe immediately over the insole. Suitable heating elements such as the electrical resistances 22 may be incorporated in the foot support to produce internal heating of the filler, as in Figs. 1 and 2, or the resistance elements may comprise the ribbons 28 laid between the foot support and the insole, as in Fig. 3. In either case, suitable leads 26 are provided which may be connected to a battery or other source of electricity. The leads may be cut off or covered up after use of the heating elements. A sock lining 24 is laid over the foot support. The sock lining is preferably composed of insulating material such as asbestos, or the envelope of the foot support may include asbestos or other insulation. According to my invention the filling material 20 of the foot support is thermoplastic or of a composition which is subject to a physical or a chemical change upon heating. For example, the material may be initially hard but capable of being softened and made moldable upon heating, or the material can be initially plastic and moldable but capable of being hardened upon heating. In either case, the structure disclosed provides for heating of the foot support in a convenient manner.

The filler for the envelope of the foot support may comprise thermoplastic or fusible substances either alone or in mixtures with each other or with inert fillers. It is preferable to use compositions which soften to a plastic, moldable state at relatively low temperatures. Such materials as glues, paraffins, waxes, rosins, gums, asphalts, pitches, shellac, latex, etc. could be used.

The filler for the foot support could comprise a composition that is moldable at normal temperatures, but upon heating, such as by the electrical heating means described, would be transformed to a rigid body and retain a foot impression. For example, a mixture of rubber and hardening agents, such as sulphur, could be used as the filler. Heating either internally or externally would vulcanize the rubber to retain the foot impression which is taken while the filler is in a moldable state.

Also, metals or alloys of metal which fuse at low temperatures could be used. Various alloys of bismuth, lead and tin either with or without cadmium or mercury might be used. A quinter-

nary alloy of bismuth, lead, tin, cadmium and indium which melts at a temperature of approximately 50° C. might be found satisfactory.

When a fusible metal alloy is employed the 5 fabric retaining envelope is not required as the metal alloy will be heated only sufficiently to permit molding by the pressure of the foot and not to a molten state.

A metallic foot support could be made composed of a fusible alloy having a thin coating or shell of metal, which has a higher melting point, enclosing the fusible metal. Upon heating the interior of the foot support would become soft and moldable and the external metal would be 15 sufficiently thin to permit flexure under pressure of the foot.

Shoes constructed as above described may be fitted to the feet and worn the same as ordinary shoes, but when desired may be transformed 20 to provide a more perfect fit and support for the foot. Thus by heating the foot support while the shoe is on the foot, the foot support will become plastic and moldable under pressure of the foot. The heat will be insulated from the foot and prevent 25 discomfort. After the foot impression has been taken it will be retained upon cooling. If a different type of filler is employed the heating will cause hardening of an initially moldable mass, and the foot impression will be retained on cooling. 30

The foot supports described above could, if desired, be placed between the insole and outsole, especially if the insole is of lightweight, flexible material or has been perforated or slashed to 35 make it more flexible.

The envelope is preferably composed of flexible, inelastic material usually fabric, but a thin flexible metallic envelope could be made having a thermoplastic filler or the envelope could be of an 40 alloy which is rigid when cold but becomes moldable when heated.

Instead of using electrical heating means, it is obvious that other forms of heating might be employed, for example, the foot support or shoe 45 could be made with a pocket to receive chemicals which would produce sufficient heat to soften the thermoplastic filling material or the fusible alloys of which the foot support is formed.

It should be understood that the foot support 50 which is combined with the heating means com-

prises an envelope and a filler which is capable of a physical change while heating. The physical change may be either from a normal, rigid state to a plastic moldable state which will permit a foot impression being taken, the filler then being permitted to cool and harden to retain the impression, or the filler may be initially in a plastic moldable state so that a foot impression may be taken, and upon heating capable of being transformed to a hard, rigid state to retain the foot 10 impression. 5

In the appended claims the wording "thermoplastic filler" is intended to cover either form of filler, namely, a filler that is softened by heat to render it moldable and permit a foot impression to be taken and then is allowed to cool, harden and retain the impression, or a filler which is normally moldable and is transformed by heating to a hard rigid state to retain a foot impression. 15 20

I claim:

1. A foot support comprising an envelope, a thermoplastic filler retained by said envelope, and heating means within the envelope. 25
2. A foot support comprising an envelope, a thermoplastic filler retained by said envelope, and electrical heating means in said envelope. 30
3. A foot support comprising an envelope of heat insulation material, a thermoplastic filler retained by said envelope, and means for internally heating the filler. 35

4. In a boot or shoe, an insole and a foot support associated therewith, said foot support comprising an envelope, a thermoplastic filler, and internal heating means. 40

5. In combination, a shoe, a heating element therein and a foot support above said heating element, said support including a thermoplastic filler. 45

6. In a boot or shoe, a thermoplastic foot support laid over the insole of the shoe, a sock lining of heat insulation material laid over the foot support, and heating means between the insole and sock lining. 50

7. In combination, a shoe including a sole, an electrical heating element associated with the sole on the inner side thereof, a foot support laid over the heating element, and a lining of insulating material laid over said foot support, said support including a thermoplastic filling composition. 55
